(Cl. D85—2)

To the Commissioner of Patents:

Be it known that I, Norman E. Kantor, a citizen of the United States, residing at New York, in the county of Queens and State of New York, have invented a new, original, and ornamental Design for a Combined Ash Tray and Cigarette Server or the like, of which the following is a specification, reference being had to the accompanying drawing, forming part thereof.

In the drawing, the figure is a perspective view of a combined ash tray and cigarette server, or the like, showing my new design.

I claim:

The ornamental design for a combined ash tray and cigarette server or the like, as shown.

NORMAN E. KANTOR,
